UNITED STATES PATENT OFFICE.

MARY A. DAVIES, OF AMSTERDAM, NEW YORK.

KETTLE-CLEANER.

No. 822,926.

Specification of Letters Patent.

Patented June 12, 1906.

Application filed September 18, 1905. Serial No. 278,896.

To all whom it may concern:

Be it known that I, MARY ALICE DAVIES, a citizen of the United States, residing at Amsterdam, county of Montgomery, and State 5 of New York, have invented certain new and useful Improvements in Kettle-Cleaners, of which the following is a specification.

The invention relates to such improvements; and it consists of the novel construction and combination of parts hereinafter described and subsequently claimed.

Reference may be had to the accompanying drawings, and the reference characters marked thereon, which form a part of this 15 specification.

Similar characters refer to similar parts in the several figures therein.

Figure 1 of the drawings is a view in isometrical perspective of my improved cleaner. 20 Fig. 2 is a like view of a strip of thin sheet metal laid out flat and adapted to be bent up to form the improved cleaner. Fig. 3 is a side elevation of the improved cleaner, showing a modified form of construction. Fig. 4 25 is a top plan view of the modified form shown in Fig. 3.

The sheet-metal strip is bent into the form shown in Fig. 1, so that approximately one half of the strip forms a ring 1 and the other 30 half of the strip forms a combination handle and cleaner 2, wherein the end 3 of the strip is bent back upon the ring and connected therewith by soldering, brazing, or in any known manner, forming the comparatively 35 sharp edge 4 at the extreme end of the V-shaped handle portion. The end 5 of the strip is also firmly secured to the body portion of the strip, as by soldering or brazing, thereby giving rigidity to the ring 1, also 40 rigidity to the handle portion, both sides being rigidly fixed relatively to the ring by the soldered connection of the two ends 3 and 5. I am thus able to cheaply and easily construct a rigid and solid structure from a single piece of 45 sheet metal which is especially adapted for use as a cleaner of dishes and kettles.

When it is desired to clean a plane surface, the device is so applied that the whole of one end comes in contact with the surface to be 50 cleaned—that is, one end of the ring portion

and one end of the handle portion—whereby the comparatively sharp edge of both the ring and handle portions may be simultaneously brought into contact with the plane surface and the surface thoroughly cleaned 55 of substances adhering thereto by a movement of the implement along such surface.

When it is desired to clean concaved surfaces—as, for example, the bottom or sides of a kettle—the concaved edge of either end 60 of the ring can be employed and the implement so inclined that the curved surface of the implement will correspond with the curve of the kettle-surface.

When it is desired to clean the angular portions found in dishes of rectangular shape, the corners 6 and 7 of the handle can be inserted therein. The edge 4 can also be brought in contact with the vertical surface of a dish-wall. The end edges are in contact with the 70 bottom or horizontal portion of the dish, thus cleaning the bottom and sides at the same time.

When desired, the V-shaped handle may have its sharp edge inclined to the plane of 75 the end edges of the ring and handle, as shown in Fig. 3, in which 9 is the inclined edge of the V-shaped handle 10, whereby the implement is adapted to fit and clean at the same time the bottom of a dish and the upright wall when the same is inclined to the bottom of the dish, as is usual in tin dishes made rectangular in form.

In the modified form of construction the ring 12 and the half 13 of the handle is made 85 of one piece of sheet metal and the other half 14 of the handle is made of another piece of sheet metal, the latter half being soldered to the ring at 15 and to the half 13 at the edge 9, thereby forming sharp cutting edges at 90 the corners 16 of the inclined edge 9.

What I claim as new, and desire to secure by Letters Patent, is—

1. A dish and kettle cleaner consisting of a single strip of sheet metal bent to form from 95 one end portion a ring, and from the other end portion a V-shaped handle, one end extremity of the strip being firmly secured to the body of the strip to give rigidity to the ring, and the other end extremity of the strip 100

being secured to the ring portion to give rigidity to the handle.

2. A dish and kettle cleaner comprising a solid ring, and a V-shaped handle firmly secured to, and projecting from, one side of the ring, the end edges of the ring and handle being in the same plane with each other.

In testimony whereof I have hereunto set my hand this 15th day of September, 1905.

MARY A. DAVIES.
